UNITED STATES PATENT OFFICE.

CHARLES BREWSTER STEELE, OF NEW YORK, N. Y.

CONVERTIBLE CAR.

1,320,654.

Specification of Letters Patent.

Patented Nov. 4, 1919.

Division of renewal application Serial No. 282,880₁, filed March 15, 1919, now Patent No. 1,308,511, dated July 1, 1919. This application filed June 7, 1919. Serial No. 302,539.

To all whom it may concern:

Be it known that I, CHARLES BREWSTER STEELE, a citizen of the United States, residing at New York, in the county and State of New York, have invented new and useful Improvements in Convertible Cars, of which the following is a specification.

My invention is a convertible car that can be instantly converted and reconverted, 10 vice versa, from a closed storm sealed "winter-car" or a wide open safely shielded "summer-car," one of my cars thus reliably delivering the service heretofore obtained from two cars, enabling railways to eliminate 15 maintenance and expense of a double equipment of summer and winter rolling stock; a single car thereby sustaining universal and efficient schedule during all varieties of climatic changes for every day of 20 the year.

Another object of my invention consists in the easily accomplishable conversion or reconversion to and from a "winter" and "summer" car while the vehicle is actively 25 engaged in traffic operation without stops or interference with its schedule service.

Another object of my invention consists in the sash, panels, and safety guards constituting ingredient constituents of the regular 30 car structure; always in operative position, condition, and readiness for instant use.

Another object of my invention consists in the safe and efficient manner in which the persons, limbs, and clothing of occupants 35 of the car are shielded from accident and danger when the car is wide open.

Another object of my invention consists in trussing the window uprights with one another by longitudinal arm-rests that form 40 compound top and bottom sills for the sash, panels, and safety guards.

Figure 1 is a side elevation of a car, broken away, showing a sash and panel weather sealing a window-opening, with an 45 adjacent window opening unsealed and exposed; the sash raised out of the window-opening; a panel dropped into its pocket, and the safety guard in position shielding the exposed window-opening.

Fig. 2 is a vertical cross section of Fig. 1,

cut through the weather sealed closed window-opening.

Fig. 3 is a fragmentary cross section reproduction of Fig. 3 from the drawings of my copending application for convertible cars, Serial No. 282,880₁, renewed March 15, 1919, now Patent No. 1,308,511, dated July 1, 1919, of which this application is a division, showing an exposed window-opening shielded by a safety guard.

Fig. 4, is a cross section of Fig. 3, cut beneath compound sill-armrests looking toward the car flooring.

Fig. 5 is a cross-section of Fig. 2, cut above the compound sill-armrest looking toward the carlines, all of which is hereinafter more fully described in the specification, defined in the claims, and illustrated in the accompanying drawings, in which like numerals represent like parts in the different 70 figures respectively.

The numeral, 1, represents the car body lower structure, and 2, the roofing structure, 3 designates window-uprights, or posts, and 4, the car flooring. Window openings, 5, 75 extend approximately from the carlines to the car flooring, divided by compound sill-armrests, 6, that brace and truss the uprights, 3, to one another along the longitudinal plane of the car structure, said compound sill-armrests, 6, having a top sill, 7, upon which the sash lower section, 8, seats, when the sash sections, 8, and 9, are in closed position and seal the window-opening, 5, 80 above the compound sill-armrests, 6, that performs several functions in addition to their own.

The numeral, 10, represents the panel that closes the lower portion of the window-opening, 5, when in raised position, and is 90 weather sealed by the overlapping drip-sill, 11, said panel, 10, dropping down within the pocket, 12, formed between the uprights by the side-wall, 13, and the side sills 14 and 15, to expose the window opening, which 95 is shielded and protected by the safety guard, 16, as shown in Fig. 3.

The safety guard, 16, may be housed within the pocket, 12, when the panel, 10, is raised to seal the window-opening, 5, but 100

the safety guard, 16, may be permanently affixed, within the window opening, against the bottom of the compound sill-armrest, 6, as shown in Fig. 3, and the panel, 10, thus 5 movably operate without and within the pocket, 12, to expose and seal the lower portion of the window opening, in coöperation with the operative movement of the sash sections, 8, and 9, that expose or seal the 10 upper portion of the window openings.

It is apparent that any type of sash and their operation, types of panels, guards, and sill-braces may be employed, and that the sash may raise or fold into the roofing 15 space, or otherwise expose the openings, or the panels may move into or out of a pocket, or such elements perform any equivalent functions without departing from the broad spirit of my invention.

20 The simplicity of standardized construction, ease and efficiency of operation; practical and instantaneous conversion and re-conversion of a storm proof weather sealed "winter car," vice versa, to and from a wide- 25 open air circulating ventilated "summer car" constitutes this vehicle a luxurious convenience of public service, and economic factor in the maintenance and operation of public transportation utilities.

30 I claim:

1. A car having a floor, walls, and roof, window openings in the walls, pockets beneath the window openings, movable sash filling the window openings, movable sash in the pockets, and movable guards in the 35 pockets.

2. A car having a floor, walls, and a roof, window openings in the walls, sash filling a portion of the window openings movable 40 alternatively to expose or close a portion of the window openings, pockets in the walls, members filling a portion of the window openings movable alternatively into pockets or to close a portion of the window openings, 45 guards movable alternatively to guard a portion of the window openings or rest in the pockets.

3. A car having walls, a plurality of 50 openings in the walls, a plurality of pockets beneath the openings, movable panels and openwork guards in the pockets to alternatively close the openings, or expose the interior of the car, the open work guards alternatively shielding the openings, or resting in their pockets.

4. A car having a floor and walls, window 60 openings in the walls, storm-sealing members dividing window openings into separated spaces, sash filling separated spaces of window openings movable alternatively to expose or close the spaces, pockets in the walls, opaque members filling spaces of window openings movable alternatively into and out of pockets to expose or close spaces,

and adjustable guards movable alternatively 65 to shield exposed spaces of window openings or to rest in pockets.

5. A convertible car having a floor, walls, and roof, window openings in the walls having sills intermediate the floor and roof provided with storm sealable means on their upper and lower surfaces, members operatively movable to close or expose openings above the sills, members operatively movable to close or expose openings below the 75 sills, guards operatively movable to protect window openings.

6. A convertible car having a floor, walls, and a roof, window openings in the walls, double storm-sealing sills in the window 80 openings intermediate the roof and floor, members above the sills operatively movable to expose or close the openings, and members below the sills operatively movable to expose or close the openings, and guards 85 operatively movable in and out of the openings.

7. A car having a floor, walls, and a roof, window openings in the walls, pockets in the walls, a plurality of members in the 90 pockets movable alternatively to permit a member to shield a portion of the window openings while another member rests in the pockets.

8. A car having a floor, walls, and a roof, 95 window openings in the walls, a window sill dividing the window openings, members filling the upper divisions of the window openings movable alternatively to expose the interior of the car or to close the upper divisions of the window openings, pockets in the walls, a plurality of members in the 100 pockets movable to alternatively fill the lower divisions of the window openings, and window shields movable within and 105 without the pockets.

9. A car having a floor, walls and a roof, an opening in the walls, a member dividing the opening into a plurality of openings, members filling an opening movable alternatively to expose the interior of the car or close the opening, a housing in the walls, a member filling an opening movable alternatively into the housing to expose the interior of the car or close the opening, and 110 guards movable alternatively to guard an opening or to rest in the housing.

10. A convertible car having upper and lower structure; openings intermediate the upper and lower structure provided with 115 means movable in opposite directions to close or uncloose the openings, and guards shielding the openings when the openings are unclosed.

11. A convertible car having upper and 120 lower structure provided with openings intermediate thereof; means closing and unclosing the openings; sealable means divid-

ing and interposing the closing-unclosing means, and guards shielding the openings when the openings are unclosed.

12. A convertible car having upper and lower structure provided with openings therebetween; means dividing the openings;

means closing and unclosing the openings coöperating with the dividing means to seal the openings when the openings are closed, and guards shielding the openings when the openings are unclosed.

CHARLES BREWSTER STEELE.
